US0D1084046S

(12) **United States Design Patent** (10) **Patent No.:** **US D1,084,046 S**
(45) **Date of Patent:** **** Jul. 15, 2025**

(54) **AUTONOMOUS LAWN MOWER**

(71) Applicant: **Scythe Robotics, Inc.**, Longmont, CO (US)

(72) Inventors: **Robert Johnstone McCutcheon, IV**, Longmont, CO (US); **John Gordon Morrison**, Longmont, CO (US); **Isaac Heath Roberts**, Longmont, CO (US); **Kevin Peter McGlade**, Denver, CO (US); **Davis Thorp Foster**, Boulder, CO (US); **Matthew Alexander Kaplan**, Bellvue, CO (US); **Zachary Austin Goins**, Boulder, CO (US); **Matthew G. Quick**, Erie, CO (US)

(73) Assignee: **SCYTHE ROBOTICS, INC.**, Longmont, CO (US)

(**) Term: **15 Years**

(21) Appl. No.: **29/888,964**

(22) Filed: **Apr. 6, 2023**

Related U.S. Application Data

(62) Division of application No. 29/851,704, filed on Aug. 31, 2022, now Pat. No. Des. 985,624, which is a division of application No. 29/760,952, filed on Dec. 4, 2020, now Pat. No. Des. 965,030.

CLAIM

The ornamental design for an autonomous lawn mower, as shown and described.

DESCRIPTION

FIG. 1 is a perspective view of an autonomous lawn mower, showing our new design;

FIG. 2 is a front view of the design shown in FIG. 1;

FIG. 3 is a rear view of the design shown in FIG. 1;

FIG. 4 is a left side view of the design shown in FIG. 1;

FIG. 5 is a right side view of the design shown in FIGS. 1;

and,

FIG. 6 is a top view of the design shown in FIGS. 1.

The broken lines shown in the Figures are included for the purpose of illustrating portions of the autonomous lawn mower and form no part of the claimed design.

1 Claim, 6 Drawing Sheets
